LIGHTING FIXTURE CONSTRUCTION

Jo Mielziner and Joseph Levy, New York, N. Y.,
assignors to Century Lighting, Inc., a corpora-
tion of New York

Application November 16, 1939, Serial No. 304,716

4 Claims. (Cl. 240—47)

This invention relates to electric lighting fixtures or units and more particularly is directed to electric lighting fixture and unit constructions for projecting light beams either as spot or flood light in various selectively desired directions from such unit.

Among the objects of the invention is to generally improve lighting fixture or unit constructions of the character described which shall comprise few parts of simple construction, particularly when manufactured of molded so-called "plastics" parts that are readily assembled to form a structure of attractive and ornamental appearance, which shall be easily adjusted for projecting light beams as spot and flood light in various desired directions, which shall be relatively inexpensive to manufacture, and practical and efficient to a high degree in use.

Other objects of this invention will in part be obvious and in part hereinafter pointed out.

The invention accordingly consists in the features of construction, combinations of elements and arrangement of parts which will be exemplified in the constructions hereinafter described and of which the scope of application will be indicated in the following claims.

In the accompanying drawings, in which are shown various possible illustrative embodiments of this invention,

Fig. 1 is a perspective view showing a portable type of light projecting unit or fixture constructed to embody the invention;

Fig. 2 is a cross-sectional view taken centrally through the unit shown in Fig. 1 to expose the interior construction;

Figs. 3, 4 and 6 are sectional views as seen from lines 3—3, 4—4 and 6—6 in Fig. 2;

Figs. 5 and 7 are fragmentary cross-sectional views corresponding to cuts taken on line 5—5 in Fig. 3 and on line 7—7 in Fig. 6, respectively;

Fig. 8 is a front elevational view of the casing body sections showing said sections in separated position;

Fig. 9 is a fragmentary perspective view showing an upper interconnecting body section joint in separated position; and

Fig. 10 is a fragmentary perspective view of a lower interconnecting lateral projection or male end stud of the right hand casing body section shown in Fig. 8.

Referring to the drawings, 20 denotes a portable light projecting fixture or unit construction embodying the invention adapted to be used for illumination in and about dwelling, show rooms, display windows, and other purposes, particularly

to provide spot or flood lighting projected in various desired directions in the manner hereinafter described.

As shown from Fig. 1 the fixture or unit 20 is provided with a base 30 adapted to rest on a horizontal support surface S or against any other suitable surface, such as the side walls of a building or mounted on the ceiling (not shown) in the well understood manner. Said base 30 has adjustably mounted thereon for universal movement through the construction hereinafter described, a housing in the form of a spherical or globular casing 40 which encloses a source of light, as for example, an electric incandescent bulb B. Said casing 40 has an opening 40a fitted with a bezel 45 carrying a lens L as shown in Figs. 1 and 2. The parts of unit 20 such as the base 30 and housing 40, particularly the latter, may be molded of the so-called "plastics" material of such grade that retains its initial physical properties and appearance even after long and continuous exposure to heat generated by the bulb B of the light source. The use of such "plastics" material which may be a phenol condensate product such as "Bakelite" is desirable since it can be manufactured economically in quantity production requiring no machining or surface finishing and therefore provides such molded parts ready of assembly to form an attractive appearing and ornamental structure.

The base 30 may be of any suitable shape and of sufficient size to steadily support the unit 20. As seen from Figs. 1, 2, 3 and 6, said base 30 comprises a stepped ring member 31 which has a central circular opening 31a, the rim flange 32 of which engages with a complementary stepped circular rim 33 of an upstanding coupling rocker clamp member 34.

Said coupling rocker clamp member 34 may be provided with integrally formed spaced jaws or shoes 35 which frictionally engage spaced arcuate shaped tracks 41a and 42a which extend around the substantially hemi-spherical or bowl-shaped body casing sections 41 and 42, respectively, of the casting 40. To retain the coupling clamp member 34 in alignment on base ring member 31 so that the same may be rotatably adjusted with respect to said ring member 31 for swivelling the casing 40 on the base 30, a flat filler disc 36 is provided on the under recessed side of the base 30 which is firmly attached in position by any suitable means and as shown in Figs. 2 and 3 by screws 37. The ring member 31 may also be provided with spaced edge openings 31c adapted to receive suitable means such as nails or screws 35.

(not shown) for positively fastening the unit 20 to the supporting surface in the well understood manner.

As seen from the drawings the globular casing 40 not only includes the bowl-shaped body sections 41 and 42 but also an arcuate louvre separator 43 which in the assembled casing 40 may be positioned between adjacent channel sides of said tracks 41a and 42a. Said separator 43 as seen from Fig. 2 is formed with spaced outwardly extending radial teeth or fins 43a which not only increase the heat radiating surface, but also serve as an ornamental trimming enhancing the attractive appearance of the unit 20. Said separator 43 also has the opposite lateral sides 43b thereof formed so as to leave tortuous passageways 43c (indicated in Figs. 2 and 3 by dot and dash arrowed lines) which extend along substantially the entire length of the adjacent surfaces 20 of the tracks 41a and 42b. Said passageways 43c provide ventilating means to permit circulation of cooling air, thus communicating the interior of the casing 40 with the exterior thereof, yet forming a barrier to prevent passage of stray 25 light beams therethrough. The louvre separator 43 has its ends 43f and 43e terminating in an upper male end stud or header 41b of track 41a and a lower male end stud or header 42b of track 42b, respectively. There may be provided 30 spaced threaded holes 43d in said separator 43 for receiving screws 44 which pass through aligning openings in the ribs 41c and 42c of the tracks 41a and 42a, respectively, as shown in Fig. 5, to retain body sections 41 and 42 and said separator 43 as a rigid structure forming the casing 40.

The lens L may be removably fitted into bezel 45 by a spring snap wire 46, suitable grooves 45a being provided for seating said wire 46 as shown in Figs. 2, 4 and 7. Other grooves similar to 40 grooves 45a and parallelly spaced therefrom may be provided to accommodate lenses of different thickness or additional color screens in abutment with the lens (not shown) in the well understood manner.

For removably mounting the bezel 45 from the casing opening 40a, any suitable interlocking means may be provided, as for example, spaced slots 40b in casing 40 which permit free insertion 50 of a spring member 47 and by rotating the bezel so that said spring member 47 engages the rim of the opening 40a. The bezel may be removably held in position as shown in Figs. 7 and 8.

The electric bulb B preferably may be of the 55 concentrated filament type and is mounted to be connected in circuit with conductor wires W in a socket receptacle 50 which may also carry a suitable reflector R for projecting the light beams received thereon from the bulb B back 60 through the lens L as is clear from Fig. 2. The socket receptacle 50 with bulb B are slidably mounted in the casing 40 on a cradle carrier 52 which is reciprocally guided by projecting ends 52a and 52b thereof along a long screw 53, said 65 screw 53 being located in spaced parallel alignment with a distance adjusting feed screw 54 for controlling the socket receptacle 52 and bulb B for straight line movement to and away from the lens L.

The screw 53 is inserted through a hole 40c in 70 the rim of the casing opening 40a in body section 42 and may be anchored in a threaded hole 40d of a boss 40e molded as part of the rear portion of the body section 42, as shown in Figs. 2, 3, 4 and 6. The adjusting feed screw 54 passes

through the lower lateral projection or male end stud 42b of the body section 42 and has a rearward extending end 54a journaled in a bearing 40f in another boss 40g, preferably molded as part of said body section 42. 5

A collar 55 spaced from a knob head 56 retains said feed screw 54 in assembled position but permits rotation thereof for advancing or retracting a threaded rider 57 along said screw 54, said rider 57 being attached to move with the cradle carrier 10 52 with the socket receptacle 50 and bulb B as shown in Figs. 2 and 4.

The conductor wires W may pass through spaced passages 40h of the casing 40, said wires W being connected to terminals of the base of 15 the bulb B in any conventional manner, as for example, shown in Figs. 2 and 4. Since the conductor wires W freely pass through the passage 40h, they do not interfere with the adjustment of the distance of the bulb B with respect to the lens 20 L when the screw knob 56 of screw 54 is manipulated.

In practising the invention with the fixture or unit 20 the parts are made and assembled as described above and shown in the drawings, the 25 unit 20 being positioned in a convenient location for use and conductor wires W connected to a suitable power source in the well understood manner (not shown). With the parts positioned as shown in Fig. 2 the optical system is so arranged that the light beams produced by the bulb B and reflected will be projected through the lens L as a spot light.

To change the character of the lighting projected from the fixture or unit 20 from spot to 35 flood lighting, all that is necessary is to vary the optical system by rotating the screw knob 56 provided on the casing 20 just under the lens L until the carrier 51 with the socket receptacle 50 and bulb B are positioned closely to the lens L. 40

The light beam may be projected in various radial positions other than that shown by a simple universal swinging movement of the casing 40 of sliding and swivelling thereof on the base 30. The swivelling movement takes place 45 by rotating the casing 40 with the upstanding member 34 with respect to the ring member 31 of the base 30. The sliding movement permits the casing to be moved in a curved path by means of the frictional engagement of the jaws or shoes 50 35 on the arcuate shaped tracks 41a and 42a. These movements permit the lens to be directed radially in any set vertical plane in which the casing 40 may be located by rotation by the swivelling movement provided in the base. Both 55 the sliding and swivelling movements permit universal movement of the projected light beams in various selectively desired directions.

The bulb B may be inspected and replaced by removing the lens L and the bezel 54 from 60 the opening 40a of the casing 40 to give access to the interior of the unit.

The tracks 41a and 42a and separator 43 may extend about the casing 40 and terminate just short of the casing opening 40a so that ventilation 65 may be provided along and through such entire exterior side of the casing 40 between said tracks 41a and 42a through the passageways 43c, said passageways being tortuous, that is, zigzag. No light beams from the interior of the casing are 70 visible on the exterior thereof.

While in the drawings and above description there is shown an embodiment of the invention in which the casing 40 is formed of three main parts, namely, two body sections 41 and 42 and 75

separator 43, a form that is believed to be economical to manufacture, it is to be understood that a casing construction with fewer main parts embodying the invention may be produced, if desired, by utilizing more expensive molding apparatus than is necessary for the above disclosed form.

It will thus be seen that the lighting fixture and unit construction as provided achieve the objects of the invention and are well adapted to meet the conditions of practical use in an efficient manner.

As various embodiments might be made in the above invention and as various changes might be made in the embodiments above set forth, it is to be understood that all matters herein set forth or shown in the accompanying drawings are to be interpreted as illustrative and not in a limiting sense.

Having thus described our invention, we claim as new and desire to secure by Letters Patent:

1. In a fixture construction of the character described, a casing comprising bowl-shaped body sections and an arcuate separator fitted together to form a globe with an opening, a lens seated in said opening, a light source enclosed in the globe located to project light beams through

the lens, and means supported on one of said sections for movably mounting said light to vary the character of the light projected from the lens.

2. In the fixture construction defined in claim 1 in which tortuous passages are provided between said arcuate separator and body sections to provide ventilating means between the interior of the globe and the exterior thereof.

3. In a fixture construction for housing a light, a casing of assembled parts forming a globe including bowl-shaped body sections, track portions extending about each body section, a louvre separator inserted between said track sections to provide ventilating means for the light in the globe, and a coupling mounting having slideable 15 shoes for engaging said track portions.

4. In a fixture construction of the character described, a louvre separator adapted to be inserted between two bowl-shaped body sections to form a globe for enclosing a light source, and 20 heat radiator fins on said separator, said separator having portions adapted to provide walls of tortuous passage between the separator and the body sections.

JO MIELZINGER. 25
